Primary Examiner — Patricia A Palasik(74) *Attorney, Agent, or Firm* — Studebaker & Brackett PC(57) **CLAIM**

The ornamental design for an industrial robot, as shown and described.

DESCRIPTION

FIG. 1 is a front perspective view of the front, right, and top sides of an industrial robot showing our new design; FIG. 2 is a rear perspective view of the rear, left, and top sides;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines shown represent unclaimed subject matter of the industrial robot and form no part of the claimed design.

1 Claim, 8 Drawing Sheets(56)
